(57) **CLAIM**

The ornamental design for a jacket with zip fastener, as shown and described.

DESCRIPTION

FIG. 1 is a front view of a first embodiment of a jacket with zip fastener, wherein a zip fastener is disposed on each side of the jacket;

FIG. 2 is a front view of a second embodiment of a jacket with zip fastener, wherein a zip fastener is disposed on the left-hand side of the jacket; and,

FIG. 3 is a front view of a third embodiment of a jacket with zip fastener, wherein a zip fastener is disposed on the right-hand side of the jacket.

The front hat elements are limited to the shapes as shown in the front view of FIG. 1, FIG. 2, or FIG. 3.

The one or more trim elements are substantially parallelogram shapes as shown in the front view of FIG. 1, FIG. 2, or FIG. 3 and have any thickness.

The upper arm elements proximate to the shoulder elements are triangular shapes extending from the sleeve as shown in the front view of FIG. 1, FIG. 2, or FIG. 3 and have any thickness.

The sleeve elements are triangular in shape, are raised from the sleeve in the front view of FIG. 1, FIG. 2, or FIG. 3, and have any thickness.

The small rectangular elements are zipper stops as are known in the art and form no part of the claimed design.

The collar is a high wrap-around collar as shown in the front view of FIG. 1, FIG. 2 or FIG. 3.

The zipper pulls have a teardrop shape as are known in the art and form no part of the claimed design.
